UNITED STATES PATENT OFFICE

ERNEST STROUD, OF LONDON, ENGLAND

DESIGN FOR A GLASS PANEL FOR LUMINAIRS

Application filed February 21, 1931. Serial No. 38,782. Term of patent 7 years.

To all whom it may concern:

Be it known that I, ERNEST STROUD, a subject of the King of Great Britain, and a resident of London, England, have invented a new, original, and ornamental Design for a Glass Panel for Luminairs of which the following is a specification, reference being had to the accompanying drawings forming a part hereof.

In the drawings:

Figures 1 and 2 are diagrammatic plan and side elevational views of the glass panel for luminairs.

Figures 3 and 4 are enlarged fragmentary top plan and inverted plan views showing the flutes and depressions appearing in the front or outer and inner or rear surface of the glass, respectively.

Figure 5 is a view similar to Figure 3 showing in additional light lines the ornamentation on the rear or inner surface as it appears from the front or outside, and

Figure 6 is a fragmentary sectional view.

The glass panel is in the form of a shallow dish with the contour of a frustum of a right pyramid on a right angled quadrilateral base, the sides of the pyramid bearing crossed flutes A and B, and the top of the pyramid bearing opposed depressions C and D, the flutes and depressions acting to diffusely transmit light.

I claim:

The ornamental design for a glass panel for luminairs substantially as shown and described.

ERNEST STROUD.
